(57) **CLAIM**

The ornamental design for a log transport tool hook, as shown and described.

DESCRIPTION

FIG. 1 is a top, front, right perspective view of a log transport tool hook;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof; and,

FIG. 8 is a left side perspective view showing a log transport tool hook being grasped by a user.

The broken lines showing of the person in FIG. 8 illustrates the environment of the claimed design and forms no part thereof. The remaining evenly spaced broken lines in the drawings illustrate portions of the log transport tool hook and form no part of the claimed design. The dot-dot-dash broken lines in the drawings define the bounds of the claim and form no part thereof.
